UNITED STATES PATENT OFFICE

131,209

DESIGN FOR A COMBINED CLOCK AND PICTURE-HOLDING CASE

Samuel J. Kauffman, New York, N. Y.

Application April 15, 1941, Serial No. 100,390

Term of patent 3½ years

To all whom it may concern:

Be it known that I, Samuel J. Kauffman, a citizen of Russia, residing at New York city, in the county and State of New York, have invented a new, original, and ornamental Design for a Combined Clock and Picture-Holding Case, of which the following is a specification; reference being had to the accompanying drawing, forming part thereof.

The figure is a perspective view of a combined clock and picture-holding case, showing my new design.

The dominant features of the design reside in

the round cornered, substantially rectangular supporting plate, and in the triangular arrangement of the three circular apertures, the upper aperture being for the reception of a clock and the two lower apertures which form the base of the triangle for the reception of photographs and the like.

I claim:

The ornamental design for a combined clock and picture-holding case, substantially as shown and described.

SAMUEL J. KAUFFMAN.
